UNITED STATES PATENT OFFICE

2,577,243

HEATING DEVICE

Torsten Ragnar Günther, Tranås, Sweden, assignor to Fritz Lundbergs Skinnberederi & Fareri Aktiebolag, Tranås, Sweden, a corporation of Sweden

Application December 27, 1948, Serial No. 67,452
In Sweden January 13, 1948

2 Claims. (Cl. 219—19)

1

The present invention relates to electric heating devices, and particularly to such as are adapted to heat rotatable rolls of ironing machines.

One object of my invention is to make provision for a more rapid heating of a hollow cylindrical ironing roll than has hitherto been possible with rolls having electric heating-elements contacting the inner peripheral surface of the roll.

Another object of my invention is to prevent over-heating and consequent damaging of the heating-resistors of heating elements for an ironing roll of the kind mentioned due to the comparatively slow heat transfer associated with such rolls having electric heating elements contacting the inner peripheral surface of the roll.

Another object of my invention is to make provision in heating devices for hollow cylindrical ironing rolls, for permitting thermal extension and contraction of the heating-resistors thereof in order to ascertain a longer life of the latter than has hitherto been possible with fixed heating-resistors.

Other objects and advantages of my invention will be set forth hereinafter, reference being had to the accompanying diagrammatic drawing in which:

Fig. 1 is a side-view of an ironer in accordance with my invention;

Fig. 2 is a cross-section on a larger scale along the line II—II in Fig. 1; and

Fig. 3 is a side-view of a resistance-helix associated with an insulation-tube in accordance with this invention.

In the conventional heating-arrangement for the hollow cylindrical roll of an ironing machine for fur, the heating is accomplished by means of heating-elements contacting the inner surface of the roll. On account of the comparatively low rate of heat transfer from such elements to the roll, the heating-resistors of such elements are liable to be overheated and thus burnt down. Another disadvantage involved in such elements consists in that the heating-resistors are fixedly positioned whereby no thermal expansion and contraction is permitted. This is a matter of great importance for the durability of the heating-resistors.

The disadvantages indicated, according to the present invention, are avoided by disposing electric resistance-helices 4 (see Fig. 3) inserted in insulation-tubes 5 in longitudinal bores 3 (see Fig. 2) provided in the roll 1. For facilitating

2

the electric connection of either the heating-resistors 4 mutually with each other, or with the source of current 6 (see Fig. 1), it may be convenient to attach the ends (2) of the resistance-helices (4) to insulating plates 9 perpendicular to the axis of the roll 1 and consisting of any suitable heat-resisting material, and provided with contact elements such as slip-rings 10 cooperating with brushes 11 (Fig. 1).

10 The invention, of course, should not be considered to be limited to the embodiment described and illustrated, as it is believed to be applicable to any kind of rotatable rolls required to be electrically heated.

15 What I claim and desire to secure by Letters Patent is:

1. A rotatable roll having an electric heating device, the peripheral portion of said roll having longitudinally extending bores therethrough, 20 a heating resistor in the form of a helix, insulation tubes surrounding said resistor and said resistor having an external diameter less than the internal diameter of the insulation therearound whereby thermal expansion and contraction of the helices is possible, said insulated heating resistors being inserted in each said bore, said heating resistors being entirely surrounded by and embedded in the material of said roll to be heated, insulating plates arranged externally of 30 said roll and perpendicular to the axis thereof, slip rings constituting contact elements on said insulating plates, the ends of the heating resistors being connected to said contact elements on said insulating plates, and brushes for cooperation with said contact elements for connecting the heating resistors to a source of current.

2. A rotatable roll having an electric heating device, the peripheral portion of said roll having a plurality of longitudinally extending bores therethrough, insulating tubes inserted in said bores, a heating resistor in the form of a helix slidingly disposed in each said tube in said bores, said resistors having an external diameter less 45 than the internal diameter of the insulating tubes whereby said resistors are enabled to change their length upon heating and cooling thereof without obstruction to such movements in said insulating tubes, said tubes being entirely surrounded by the material of the roll to be heated.

TORSTEN RAGNAR GÜNTHER.
